UNITED STATES PATENT OFFICE

2,466,065

DIRECT-CURRENT AMPLIFIER AND
CIRCUIT

Heinz Hermann Weichardt, New York, N. Y., assignor to Tung-Sol Lamp Works, Inc., Newark, N. J., a corporation of Delaware

Application September 8, 1944, Serial No. 553,178

16 Claims. (Cl. 315—15)

1

My invention relates to amplifier tubes and more particularly to low voltage D. C. amplifier tubes and circuits therefor.

An object of the invention is to provide an amplifier of this type that will be small, about the size of the conventional receiving tube, and will have a high amplification factor.

Another object of the invention is to provide a low voltage direct current amplifier in which the control electrode or "grid" may be operated at potentials positive with respect to that of the cathode.

A further object of the invention is to provide an efficient electron beam forming and focusing lens in a low voltage direct current amplifier.

In the accompanying drawing—

Fig. 1 is a diagram of the elements of an amplifier tube embodying the invention; and

Fig. 2 is a circuit drawing showing the tube connected for amplification of voltage variations of a photocell.

My new amplifier is shown at 20.

In Fig. 1, 1 represents diagrammatically any suitable evacuated envelope for the elements of the new amplifier, which elements include a cathode 2, preferably of the indirectly heated type, an electronic lens comprising slotted electrodes 4 and 6 and a mesh electrode 8 positioned therebetween, a control electrode 10, a target 12, a suppressor grid 14 and an electrode 16 adapted to be maintained at the potential of the electrode 6, as by the connection 18 therebetween.

In use, mesh electrode 8 is maintained at a potential substantially higher than that of electrode 6. Thus if electrodes 6 and 16 are at potential V , electrode 8 will be at a potential of $V+x$ where x is positive. The potential of electrode 4 may be equal to that of the cathode, or it may be negative with respect thereto. The three electrodes together form an electronic lens, the equi-potential lines of which are indicated in the drawing. By forming the electrode 8 of wire mesh, the diverging effect of an intermediately positioned slotted lens of high potential is avoided. The optical equivalent of the three electrode electronic lens is the two simple converging lenses symbolically indicated at L_1 and L_2 in the drawing. The current absorbed by electrode 8 may be minimized by keeping low the ratio of wire diameter to mesh opening. At one hundred

mesh of .002" wire serves satisfactorily for the electrode 8. When the potential of electrode 8 is about one and one-half times that of electrode 6 the electron beam may be brought to a focus at a point about 15 mm. from the lens. Due to the relatively low potentials employed—say from 200 to 500 volts on electrode 8, the velocity of the electrons leaving the lens is low enough for deflection by the control electrode 10 during the short distance of travel of the beam toward the target 12.

As shown in Fig. 1, electrodes 10 and 16 are elongated longitudinally of the tube so as to influence the electron beam throughout its path. Electrode 10 preferably flares outwardly to minimize the drawing of current by that electrode.

Target 12 is preferably maintained at the quiescent potential of electrode 10, which is substantially that of electrodes 16 and 6. The suppressor 14 is maintained at the cathode potential or slightly positive with respect thereto. Its function is to prevent the flow of secondary electrons from the target from reaching electrode 16 and to shield the target from electrode 16, thereby preventing the potential difference, set up during operation of the tube, from reacting on the deflection of the beam.

During operation of the tube the positive voltages, the variations of which are to be amplified, are applied to electrode 10. At the quiescent potential, that is, when the potential of electrode 10 is substantially equal to that of electrode 16, there is no deflection of the beam of electrons and hence but a relatively small part of the beam falls on the target 12. Upon an increase of potential of electrode 10 the beam is deflected to increase the flow of electrons to the target. Consequently the target potential decreases in proportion to the increase of potential on electrode 10. Upon decrease in potential on electrode 10, the beam is deflected toward electrode 16 with consequent reduction in target current and corresponding increase of potential thereof. The potential swing of the target is substantially greater than that of the control electrode 10 and hence the tube operates as an amplifier. With a tube of the size of a conventional receiving tube an amplification factor of $\mu=100$ can be easily obtained. The beam current in such

tube when the potential of electrode 6 is about two-thirds of electrode 8 is about 1 milliampere.

In Fig. 2 the new amplifier, indicated at 20, is shown with its control electrode 10, connected directly to the anode of a conventional three-electrode amplifier 21. Amplifier 21, in the particular circuit illustrated in Fig. 2, is connected to amplify voltage variations of a photocell 22. A voltage divider 24 across the ends of which a constant potential difference of a few hundred volts is maintained, has a tap 26, near the positive end, connected directly to the positive electrode of the photo cell 22 and connected through a resistor 28 to the anode of amplifier 21. The positive end of divider 24 is connected directly to electrode 8 of the lens of tube 20 and through a resistor 30 with the target 12. Electrodes 16 and 6 are connected through a lead 32 with an intermediate point on divider 24. The cathodes of both tubes 20 and 21 are connected together to a point of low potential on the divider and electrode 4 of the lens in the specific embodiment of the invention illustrated is connected to the negative end of the divider. The control grid of amplifier 21 and the negative electrode of the photo-cell are connected through a resistor 34 with a point on the divider of potential negative with respect to the cathodes.

The operation will be clear from the above description. Variations of voltage of the photocell 22 applied to the grid of amplifier 21 will appear as amplified variations in the positive potential of the anode of that tube. The varying positive potential of control electrode 10, being that of the anode of amplifier 21, will cause corresponding deflections of the beam of electrons issuing from the electronic lens with corresponding amplified voltage variations appearing on target 12. Hence amplified voltages will appear across terminals 35 and 36, connected, respectively, with the cathodes of the tubes and with the target. These amplified voltages could be applied directly across the control electrode and cathode of a succeeding tube 20 if further amplification is desired.

The amplifier requires but relatively low operating voltages and the positive potentials, the variations of which are to be amplified, can be applied directly to the control electrode or "grid" without such electrode drawing substantial current. The small size of the amplifier is made possible by the provision of the electronic lens having only converging elements to which relatively low operating potentials are applied; the lens converging the electron stream from the cathode into a beam of short focal length with the electrons thereof moving relatively slowly so as to be readily influenced by changes in the control potential.

The new amplifier tube and circuit have now been described with reference to the drawings. It will be understood that various changes in the circuit or tube elements diagrammatically shown in the drawing could be made without departing from the spirit of the invention. For example, the electrode 8 of the electronic lens has been diagrammatically illustrated as being throughout of wire mesh. As the part of this electrode aligned with the slots in electrodes 4 and 6 is the only part through which the electrons penetrate, it is not necessary that the entire electrode be of mesh. In practice the electrode 8 could, and preferably would, be made of a slotted metal sheet with wire mesh covering the slot.

The following is claimed:

1. The low voltage direct current amplifier comprising a source of electrons, an electronic

lens adapted to form the electrons from said source into a converging beam of short focus, a target adjacent the focal point of said beam and a control electrode positioned to deflect said beam upon changes of positive potential and flared outwardly therefrom.

2. In a low voltage direct current amplifier having a cathode, a control electrode and an anode target, a three-electrode electronic lens positioned between said cathode and said control electrode, said lens forming the electrons emitted by said cathode into a converging beam of short focus.

3. The combination in an amplifier tube of a cathode, control electrode, anode target and convergent electronic lens, said lens being positioned in the path of electrons emitted by the cathode and operating to form a convergent beam of short focus and said control electrode being positioned between said lens and anode target and to one side of the electron beam, said electron lens comprising two spaced slotted electrodes and a mesh electrode positioned between the slotted electrodes, said intermediate electrode being at a higher positive potential than either of said slotted electrodes and the slotted electrode nearest the control electrode being at a higher potential than the other slotted electrode whereby the optical equivalent of said lens is a pair of simple convergent lenses.

4. A low voltage direct current amplifier having a control electrode adapted to operate at positive potentials comprising in combination an evacuated envelope, a cathode, a 3-element convergent electronic lens, a target and a diverging control electrode all within said envelope, said control electrode being positioned between said lens and said target and to one side of the convergent electron beam formed by the lens and said lens being so formed that the optical equivalent thereof is a pair of simple convergent lenses.

5. An amplifier comprising in combination a cathode for emission of electrons, a slotted first electrode adjacent to said cathode and maintained at a potential not greater than that of the cathode, a second electrode maintained at a potential substantially positive with respect to the cathode, at least that part of said second electrode aligned with the slot of said first electrode being of mesh, a slotted third electrode maintained at a potential positive with respect to the cathode and lower than that of said second electrode, said three electrodes together comprising an electronic lens for forming the electrons emitted by said cathode into a convergent beam of short focus, a target positioned adjacent the focal point of the electron beam and a control electrode positioned between the lens and the target and to one side of the electron beam for deflection thereof toward and from the target.

6. An amplifier comprising in combination a cathode for emission of electrons, a slotted first electrode adjacent to said cathode and maintained at a potential not greater than that of the cathode, a second electrode maintained at a potential substantially positive with respect to the cathode, at least that part of said second electrode aligned with the slot of said first electrode being of mesh, a slotted third electrode maintained at a potential positive with respect to the cathode and lower than that of said second electrode, said three electrodes together comprising an electronic lens for forming the electrons emitted by said cathode into a convergent beam of short focus, a target positioned adjacent the focal point of the electron beam and a con-

trol electrode positioned between the lens and the target and to one side of the electron beam for deflection thereof toward and from the target and an electrode positioned between the lens and the target and on the opposite side of the beam from said control electrode, said last mentioned electrode being maintained at the potential of said third electrode.

7. An amplifier comprising in combination a cathode for emission of electrons, a slotted first electrode adjacent to said cathode and maintained at a potential not greater than that of the cathode, a second electrode maintained at a potential substantially positive with respect to the cathode, at least that part of said second electrode alined with the slot of said first electrode being of mesh, a slotted third electrode maintained at a potential positive with respect to the cathode and lower than that of said second electrode, said three electrodes together comprising an electronic lens for forming the electrons emitted by said cathode into a convergent beam of short focus, a target positioned adjacent the focal point of the electron beam and a control electrode positioned between the lens and the target and to one side of the electron beam for deflection thereof toward and from the target and an electrode disposed on the opposite side of the beam from the control electrode and maintained at the potential of said third electrode and a suppressor maintained at substantially the cathode potential and positioned adjacent the target for shielding the target and suppressing the flow of secondary electrons therefrom.

8. An amplifier comprising in combination a cathode for emission of electrons, a slotted first electrode adjacent to said cathode and maintained at a potential not greater than that of the cathode, a second electrode maintained at a potential substantially positive with respect to the cathode, at least that part of said second electrode alined with the slot of said first electrode being of mesh, a slotted third electrode maintained at a potential positive with respect to the cathode and lower than that of said second electrode, said three electrodes together comprising an electronic lens for forming the electrons emitted by said cathode into a convergent beam of short focus, a target positioned adjacent the focal point of the electron beam and a control electrode positioned between the lens and the target and to one side of the electron beam for deflection thereof toward and from the target said control electrode being operated at potentials positive with respect to the cathode and being flared outwardly from the beam to minimize the drawing of current.

9. An amplifying circuit, comprising two amplifier tubes, one of said tubes being a conventional tube having a control grid, an anode and a cathode and the other of said tubes being a low voltage direct current amplifier having a cathode, an electronic lens for forming electrons into a converging beam, a target and a control electrode positioned to deflect the beam formed by the lens, a connection between the cathodes of said tubes, a connection between the anode of said first tube and the control electrode of said second tube, and means for maintaining said anode and said target at potentials positive with respect to the cathodes whereby variations in potential applied to the control grid of the first tube appear at the anode thereof and at the control electrode of the second tube as amplified variations in positive po-

tential and appear further amplified at the target of said second tube.

10. An amplifying circuit, comprising two amplifier tubes, one of said tubes being a conventional tube having a control grid, an anode and a cathode and the other of said tubes being a low voltage direct current amplifier having a cathode, an electronic lens for forming electrons into a converging beam, a target and a control electrode positioned to deflect the beam formed by the lens, a connection between the cathodes of said tubes, a connection between the anode of said first tube and the control electrode of said second tube, and means for maintaining said anode and said target at potentials positive with respect to the cathodes whereby variations in potential applied to the control grid of the first tube appear at the anode thereof and at the control electrode of the second tube as amplified variations in positive potential and appear further amplified at the target of said second tube, said electronic lens comprising convergent elements only.
11. An amplifying circuit comprising two amplifier tubes, one of said tubes being a conventional tube having a control grid, an anode and a cathode and the other of said tubes being a low voltage direct current amplifier having a cathode, an electronic lens for forming electrons into a converging beam, a target and a control electrode positioned to deflect the beam formed by the lens, a connection between the cathodes of said tubes, a connection between the anode of said first tube and the control electrode of said second tube, and means for maintaining said anode and said target at potentials positive with respect to the cathodes whereby variations in potential applied to the control grid of the first tube appear at the anode thereof and at the control electrode of the second tube as amplified variations in positive potential and appear further amplified at the target of said second tube, said means for maintaining the potentials of said anode and target positive with respect to said cathodes comprising a voltage divider having a connection adjacent its negative end to said cathodes, a resistor connected between said anode and a point adjacent the positive end of said divider, and a resistor connected between said target and the positive end of said divider and wherein said electronic lens comprises a first slotted electrode connected to the negative end of said divider, a second mesh electrode connected to the positive end of said divider and a third slotted electrode connected to an intermediate point on said divider.

12. A direct current amplifier comprising a cathode, a control electrode, a three element electronic lens for converging the electron beam from said cathode and a target anode all within an evacuated envelope substantially the size of a conventional receiving tube.

13. A direct current amplifier comprising a source of electrons, a three element electronic lens for forming the electrons from said source into a convergent beam said lens having a center element formed at least in part of wire mesh, a target adjacent the focal point of said beam and a control electrode positioned to deflect said beam upon changes of potential.

14. A direct current amplifier comprising a source of electrons, an electron lens adapted when potentials of the order of a few hundred volts are applied thereto to form the electrons from said source into a converging beam having a focal

length of the order of 15 mm., a target adjacent the focal point of said beam and a control electrode positioned to deflect said beam upon changes of positive potential.

15. An amplifier tube comprising a source of electrons, a three element electron lens converging the beam of electrons upon the application of a relatively low voltage thereto, a target adjacent the focal point of said converging beam, a control electrode positioned between the anode and the lens to deflect said beam upon changes of positive potential applied thereto, and a suppressor grid positioned between the control electrode and the anode.

16. An amplifier tube comprising a cathode for the generation of an electron beam, an electronic lens adjacent said cathode having at least three elements, the outer elements having slots therein and the middle element being formed of a wire mesh, said lens operating to converge the electron beam, a target anode positioned near the focal point of the converging beam, a control electrode interposed between the lens and the target anode, said electrode being divergent with respect to the electron beam and operating by the application of positive potentials thereto to deflect the beam, and a suppressor grid positioned between the control electrode and the target anode to prevent secondary emission from the target anode from affecting the deflection of the beam.
